UNITED STATES PATENT OFFICE.

ARTHUR ENGEL, OF CHICAGO, ILLINOIS.

CASE-HOLDER FOR BOOKS.

1,330,250.

Specification of Letters Patent.

Patented Feb. 10, 1920.

Application filed June 2, 1919. Serial No. 301,276.

To all whom it may concern:

Be it known that I, ARTHUR ENGEL, a citizen of the United States, residing at Chicago, in the county of Cook and State 5 of Illinois, have invented certain new and useful Improvements in Case-Holders for Books, of which the following is a specification.

This invention relates to a portable case 10 designed primarily for the accommodation of books, there being combined with the case certain features which adapt it to function as a holder for the books at the time of their use. Some of these features were first 15 disclosed in Letters Patent No. 1,304,668, issued to me under date May 27, 1919.

In the present device I have aimed to provide a case which is commodious, compact, and light, and hence easily portable; a case 20 in which books are retained therein in such relation that when it is opened the books themselves are disposed ready for use; a case in which the books are held in a closely grouped arrangement convenient for inter- 25 reference purposes; and a case having a number of its component parts detachably assembled so as to facilitate transfers, rearrangements, or removals whenever desired. The invention consists further in nu- 30 merous other features of construction and combinations of parts as will more fully hereinafter appear.

A suggestive embodiment of my invention is illustrated in the accompanying drawings 35 wherein—

Figure 1 is a perspective view showing the present case-holder opened up for use, but without books therein so as to better exhibit its construction;

Fig. 2 is a plan view of the case-holder 40 opened up, the books being removed in this figure, and one book retainer—the one shown on the right—being folded;

Fig. 3 is a longitudinal section taken on line 3—3 of Fig. 2;

Fig. 4 is an enlarged transverse section through the device as it appears when closed up to form a case;

Fig. 5 is a detail, in plan, of the handle;

Fig. 6 is a fragmentary detail showing the connection for the rear book retainer;

Figs. 7 and 8 are end views showing the holder opened up, but without books, the retainers for the books being extended in the former figure, and being folded in the latter; and

Fig. 9 is a transverse section taken approximately on line 9—9 of Fig. 3.

As appears clearly in the drawings, the case-holder comprises two companion box 60 sections designated, respectively, as A and B, swingingly connected together, and each formed of corresponding parts, including a bottom designated, respectively, as 10 and 11, a fixed side wall designated as 12 and 13, respectively, these walls being arranged to lie in adjacent planes when the case-holder is opened and in coincident planes when it is closed, and fixed end walls designated as 14 and 15, in the respective box 70 sections. Swingingly secured to the box section B is a cover 16 adapted also to function as an extension wall, and having a width approximately twice that of the sides 12 and 13. A swinging flap 17 is carried 75 by the cover 16 so that when the case-holder is closed, the box sections may fold together along their hinged edges permitting the cover 16 to be lapped over the upper side of the case (which would otherwise be open) 80 and the flap 17 to be placed over the proximate end of the bottom 10 of section A, all as appears best in Fig. 4. A button 18 may be secured to the under side of the bottom 10 in position to coöperate with a socket 85 member 19 carried by the flap 17, the two parts constituting a snap fastener for holding the box sections together when the device is to be used as a case.

For convenience in carrying I have arranged upon the cover a handle which may consist of a strap 20 having each of its ends secured to the cover 16 by means of snap buttons 21, but preferably one such end is provided with a slot 22 through which the 90 shank of the proximate snap button extends freely, the purpose being to permit the handle to straighten out and lie flat upon the case whenever desired, or to assume an arched position for convenience in carrying. 100

Interiorly of the holder sections upon the ends 14 and 15, I have arranged buttons 24 adapted to coöperate with sockets 25 carried by end flaps 26 of a base 27, the parts 24 and 25 constituting a snap fastening, and mounted upon the base is a swinging frame 105 consisting of supports 28 and 29 which are hingedly secured to the base near its ends, and a board 30 carried by these supports. The section 29, which is rearward of the 110 section 28, is the longer, and when the frame is raised, the section 28 is swung from its

forward position indicated in Fig. 8 through an arc of substantially 180° to a rearward position, as shown in Fig. 9. This movement of the parts results in the section 29 5 swinging through an arc of something less than 90° so as to elevate the rear end of the board 30, the forward end being held adjacent the base by means of a snap fastening 31 which may consist of a button secured 10 to the base in coöperating relation to a socket carried by the section 28.

Hinged to one side of the board 30 as at 32 is an extension board 33 adapted when folded out to aline therewith and to be supported by partially resting thereon (see Fig. 3). Snap fasteners 34 may be used to hold the board 33 in such extended position. The board and extension so formed is adapted to receive a retaining device for a book 20 which may conveniently consist of a back member 35 having capacity for folding in its central portion, and provided with parallel retaining members 36 arranged across its face near the opposite ends thereof beneath 25 which the edges of the covers of a book may be secured. As a simple means of holding the retainer in place, I have shown snap fasteners consisting of sockets 37 secured to the back in position to coöperate with 30 buttons 38. When the extension board 33 is folded out an adequate support is afforded for the books within the retainer.

Each section of the holder is provided with a supporting frame for a book retainer 35 so as to accommodate two books in all, arranged side by side. As already noted, each retainer, together with its associated book, may be folded up, as shown in Fig. 4, also the extension board 33 may be folded after 40 it, so that the case may be closed up with the books held in position ready for use when it is again opened to function as a holder.

As a part of this invention I have arranged a retainer for a third book which is mounted rearwardly of the others, but which may be folded forwardly, when required, so as to fit within the space that is afforded within the closed case. This third retainer 45 consists of a backing member 39 having a flexible intermediate portion 40 which constitutes a hinge, parallel retaining members 41 being arranged adjacent the opposite ends of the backing member so as to receive 50 beneath them the covers of a book.

The third book retainer may be secured in place by means of a board 42 having a hinged end 43 adapted to make fastening, as by means of snap buttons 44, with the rear wall 15 of the case section B. The upper edge 45 of the wall 15 is appropriately beveled or otherwise formed to afford support to this board 42 when its hinged end 60 43 is secured in place, the relation then being such as is indicated in Figs. 7, 8, and 9.

By some such means as snap fasteners 46, the rear book retainer may be secured to the board 42. It will be noted that this board supports only one-half of the retainer, namely, the half that is proximate to the section B. To support its other half, I have provided a tongue 47 hinged to the board in a manner that permits it to swing around adjacent to the unsupported half of the retainer to which it may be secured as by means of snap fasteners 48. Such a means serve to support the retainer, and to prevent its closing up except when the snap fastening has been disconnected.

The present device, as will be noted from the preceding description, comprises two sections each containing parts substantially alike; also a third part—the rear book retainer—which may be folded into the device when it is to be closed up and used as a case. The particular materials from which the several parts are made, as well as the means for joining them together are relatively immaterial, as obviously numerous expedients for this purpose are well known. Those which have been shown and described are merely suggestive as preferred embodiments. Accordingly I do not desire to be limited in the application of my invention to only those forms which have been herein shown and described, but wish to include other equivalent and alternate structures, or modifications thereof, all as set forth in the appended claims, as follows.

I claim:

1. A case-holder comprising two hinged box sections adapted when folded together to provide a closed case, a book retainer secured within each section adapted to project beyond the sides thereof, each retainer being foldable to lie wholly within its associated section when the case is closed, substantially as described.

2. A case-holder comprising two hinged box sections adapted when folded together to provide a closed case, a book retainer secured within each section adapted to project beyond the sides thereof, and a third book retainer secured to one section adapted to lie rearwardly of the other retainers, all of the retainers being foldable to lie wholly within the case when closed, substantially as described.

3. A case-holder comprising two hinged box sections adapted when folded together to provide a closed case, a frame within each section having means thereon for holding a book retainer, each frame having capacity for elevating one of its ends whereby an inclined support is provided for the book retainer, the frame, together with the book retainer thereon, being foldable to lie within the case, substantially as described.

4. A case-holder comprising two hinged box sections adapted when folded together to

provide a closed case, a frame in each section having means thereon for holding a book retainer, each frame having capacity for elevating one of its ends whereby an inclined support is provided for the book retainer, and means for maintaining the frame in such elevated position, substantially as described.

5. A case-holder comprising two hinged box sections adapted when folded together 10 to provide a closed case, a board secured within each section having a portion extensible beyond the sides of the section and adapted, when extended, to be supported therebeyond, and a retainer supported upon each board 15 adapted to hold a book thereon, the book retainer, as well as the extended portion of the board, being foldable to lie wholly within the section, substantially as described.

6. A case-holder comprising two hinged 20 box sections adapted when opened out to exhibit in each a book, and means for carrying a third book arranged upon the rear side of one of the box sections consisting of a book retainer secured to one section and extending rearwardly thereof and of the other section as well, and means for holding the book retainer in such extended position, substantially as described.

7. A case-holder comprising a box, a

board detachably secured within the box, an 30 extensible portion swingingly secured to the board, means for supporting the extensible portion when swung out into alignment with the board, and a book retainer adapted to be supported upon the board and its extended 35 portion, substantially as described.

8. A case-holder comprising a box adapted also to function as a case, a board detachably secured within the box and having a portion extensible beyond the sides of the box adapt- 40 ed when extended to be supported therebeyond, and a retainer supported upon the board adapted to hold a book thereon, the book retainer, as well as the extended portion 45 of the board being foldable to lie wholly within the box, substantially as described.

9. A case-holder comprising a box adapted also to function as a case, a frame within the box having means thereon for holding a book, the frame having capacity for elevation at one of its ends whereby an inclined support is provided for the book, the frame, together with the book thereon, being foldable to lie within the box, substantially as 50 described.

ARTHUR ENGEL.
